TOY TRAIN CAR

Joseph L. Bonanno, South Orange, N.J., assignor to The Lionel Corporation, New York, N.Y., a corporation of New York

Application January 22, 1959, Serial No. 54,275

Term of patent 14 years

(Cl. D34—15)

Fig. 1 is a side view of a toy train car in accordance with my design;

Fig. 2 is a top plan view of Fig. 1; and

Fig. 3 is an end view of Fig. 1.

The dominant features of my design reside in those portions shown in full lines on the drawings. The side and end of the car not shown are substantially identical to the side and end shown.

I claim:

The ornamental design for a toy train car, as shown and described.
